UNITED STATES PATENT OFFICE.

HENRY P. COPE, OF DETROIT, MICHIGAN, ASSIGNOR TO THE GEM CITY STOVE COMPANY, OF DAYTON, OHIO.

DESIGN FOR A HEATING-STOVE.

SPECIFICATION forming part of Design No. 30,508, dated April 4, 1899.

Application filed January 14, 1899. Serial No. 702,186. Term of patent 7 years.

To all whom it may concern:

Be it known that I, HENRY P. COPE, a citizen of the United States, residing at Detroit, in the county of Wayne and State of Michigan, have invented and produced a new and original Design for a Heating-Stove; and I do declare the following to be a full, clear, and exact description of the same, reference being had to the accompanying drawing, forming a part thereof.

The accompanying drawing represents a front elevation of a heating-stove, showing my design.

The leading characteristics of the design consist of the particular shape and ornamentations of the stove as an entirety and also of the shape and ornamentations of the separate parts thereof, as hereinafter described.

1 indicates the base or ash-pit section of the stove. This section is provided with legs 2, the outer surfaces of which are covered with oblong-shaped scroll-like ornamentations 3. The base 1 has at its corners adjacent to the legs conventional curves or scroll-like figures 4, arranged concentrically, and the surface of said base between the scrolls 4 is covered with ornamentations or scrollwork 5, presenting the general appearance shown in the drawing. The ash-pit door 6 has a circular damper 7, with surrounding circular and oblong ornamentations 8. Above the base 1 is the fire-bowl section, having its surface covered with vertically-disposed fluting or corrugations 9. Surrounding said fire-bowl

section is a foot-rail 10, supported on closed 35 brackets 11. The outer edge of said foot-rail terminates in a series of curves 12, and the top surface of said rail is covered with ornamental designs 13, as shown. The body of the stove, just above the fire-bowl, is surrounded by a skirting, the surface of which is covered with varying curves or scroll ornamentation 14. Above the said skirting and joining it in the front of the stove is a door-panel 15, covered throughout with a massing 40 of shell and scroll work 16 and 17 and having shields 18 and 19 in central positions. The stove is surmounted with a cover or cap 20, having a plain-surfaced rim 21 at the bottom. The said cap extends upwardly in a rounded 45 form. The ornamental work on the upper portion of the cap consists of oblong and concentrically-arranged scrolls or ornamentations 22 and 23, the latter ornamentations converging at the top of said cap. The ornamentations 22 and 23 are separated from the rim 21 by a circular band having surface ornamentations 24.

I claim—

The design for a heating-stove, substantially as herein shown and described.

In testimony that I claim the foregoing as my own I hereto affix my signature in presence of two witnesses.

HENRY P. COPE.
